UNITED STATES PATENT OFFICE.

JOSEPH FRANCIS COLLINS, OF WASHINGTON, DISTRICT OF COLUMBIA.

DRAFTING INSTRUMENT.

1,109,322.

Specification of Letters Patent. Patented Sept. 1, 1914.

Application filed September 28, 1910. Serial No. 584,267.

To all whom it may concern:

Be it known that I, JOSEPH FRANCIS COLLINS, a citizen of the United States, residing at 2049 Ninth street northwest, Washington, District of Columbia, have invented certain new and useful Improvements in Drafting Instruments, of which the following is a specification.

This invention relates to an improvement in drafting instruments and has for one of its objects to provide a marking attachment, comprising a plurality of marking elements, which is primarily intended to be applied to compasses of different types, but which 15 may be used, by applying a suitable handle thereto, as a "railroad pen," or in fact as any straight line pen.

A further object of the present invention is to provide a marking attachment, which 20 may be used as a common bow pen to draw a single straight line, or by making certain adjustments therein may be converted into an instrument whereby a plurality of parallel lines may be drawn simultaneously.

25 I am aware that drawing instruments have been heretofore invented which contemplate the drawing of a plurality of lines at one time, but no instrument has heretofore been invented, in so far as I know, 30 which provides a plurality of marking elements, so arranged that any one of said elements may be adjusted into or out of marking position, and where all of said elements 35 may be brought into marking position, at the same time.

The present invention comprises a plurality of marking elements adjustably secured to a common member, and means engaging each of said elements, whereby either 40 one of them may be adjusted, vertically, into and out of marking position; the outer one of said marking elements being provided with means for laterally adjusting it in relation to the inner marking element.

45 Further objects and advantages of my invention will appear from the following description, with reference to the accompanying drawing, wherein—

Figure 1 is a view in side elevation of 50 a compass provided with my invention. Fig. 2 is a detail view of my improved attachment, partly in section. Fig. 3 is a sectional view taken on the line 3—3 of Fig. 1. Fig. 4 is a view in side elevation of a 55 modified form of my invention.

Referring more specifically to the draw-

ings, wherein like reference numerals indicate like parts throughout the different views, the numeral 1 designates a compass of the ordinary construction, comprising the 60 depending legs 2 and 3, pivotally connected, as at 4.

The leg 2 is made in two sections, which are hinged together at the point 5, the lower section of the said leg being provided 65 at its extreme lower end, with a pivot or needle 6. The opposite leg 3 has a socket formed in its lower end, wherein the reduced end of the shank 7 fits, being held in place by means of the set screw 8.

70 A yoke member 9 is secured to this shank 7 means of the hinged connection 7^a, this yoke member having a pair of alined bearings formed adjacent to the lower ends of the depending tines 9^a. On the outer face 75 of one of the tines of said yoke member, and surrounding one of the aforementioned bearings, an annular stud projects, being indicated by the numeral 10, the outer face of said stud having recesses 12 formed 80 thereon.

An abbreviated shaft 13 is adapted to pass through the alined bearings of the yoke member, one end of this shaft having a transverse lug or knife-edged pin 14 secured thereto, which is arranged to normally engage in the recesses 12, of the stud 10.

85 A suitable head is provided at the opposite end of the shaft 13, and a small coil spring 90 15 is placed thereon, whereby one end of the spring will abut against the inner face of the head while the other end will press against one of the depending tines of the yoke 9; the normal tendency of said spring 95 being to hold the lug or pin 14 in engagement with one or more of the recesses 12, whereby the shaft 13 will be prevented from rotating.

90 Rigidly mounted on the shaft 13 and located between the tines of the yoke member 9, is a small pinion 16, the function of which will be further described hereinafter.

100 The numeral 17 indicates a marking element, provided with a head portion 18, the 105 inner face thereof having rack teeth 19 formed thereon. Side plates 19 are suitably secured to said rack head, the free edge thereof being bent, thus forming flanges 20.

110 In assembling the different parts of my invention thus far described it will be seen that the side plates 21, together with the

head portion of the marking element 17, form a substantially hollow rectangular casing, which is adapted to be inserted between the tines of the yoke member 9. The 5 abbreviated shaft 13, passes through vertical slots 22, formed in the side plates 21, while the pinion 16, which is mounted on the shaft 13, will be so positioned that it will readily mesh with the rack teeth 19 of 10 the head portion, so that upon rotating the said pinion, the marking element 17 will be raised or lowered, according to the direction in which the pinion is rotated.

To insure strictly vertical movement, and 15 to prevent any lateral play of the above-named marking element, a substantially U-shaped guide is secured to the outer face of one of the side plates 21, within which one of the tines of the yoke member 9 snugly fits.

The numeral 24, indicates a short rail member, which is provided on its inner face with the rack teeth 25. This rail member has slide-ways 26, formed on each side, 25 wherein the flanged edges 20, of the side plates 21, are adapted to fit, while the rack teeth 25, are so located that they will mesh with the opposite side of the pinion 16, from that which meshes with the teeth 19 of the 30 marking element 17. On the outer face of this rail member 24, and adjacent to the lower end thereof, is the outwardly extending guide rod 25^a, while from adjacent to the top of said rail, projects an adjusting 35 rod or bar 26^b, this last named rod being parallel to the guide rod 25, and provided with screw threads throughout its length.

The marking element 27, which is substantially a duplicate of element 17, has an 40 angular head 28, the upper portion thereof being bifurcated 26^b. Two sets of bearings are formed in this upper portion, and are spaced apart exactly the same distance as are the guide rod and the adjusting rod on 45 the rail member 24.

A suitable adjusting nut 29 is inserted within the bifurcated end portion 26^b of the head 28; and in alinement with the bearings formed therein, the said nut being adapted 50 to mesh with the screw threads on the rod 26^a, when the parts are assembled.

From the above description, the operation of my device will be seen to be as follows: In the embodiment shown in Fig. 1, where- 55 in my invention is shown attached to a compass of the ordinary construction, whenever it is necessary to use the instrument to draw a single circle of extremely small diameter, the inner marking element must be used 60 alone. In this case, supposing the outer marking element to be in marking position, the shaft 13 is pressed inwardly against the pressure of the spring 15. As has been stated heretofore, this shaft carries the locking key or pin 14, which is normally held in

engagement with the recesses 12 by the spring 15, so that it will be seen that it is only necessary to force the shaft inward a sufficient distance to cause the disengagement of the locking element from the recesses 12, whereby the shaft 13, and also the pinion 16, which is carried by the shaft, may be rotated in either direction. The pinion 16 will mesh with the rack teeth formed on the marking elements, and will accordingly raise the outer marking element and lower the inner one to the desired position. The shaft 13 being released, when the marking element is in the desired position the locking element or key will immediately engage with the recesses 12 and thus securely lock the two marking elements in their adjusted positions. In some instances, however, it is necessary to draw a plurality of sets of concentric circles, as in the case 85 of illustrating an end view of a number of pipes. When used in an instance of this kind, the marking elements are adjusted in the manner as described above except that the marking points thereof are brought into 90 alinement, the outer marking element being adjusted laterally by means of the adjusting nut, until there is a sufficient distance between the two elements; as, for instance, to indicate the thickness of the pipe, after 95 which adjustments have been made the instrument is used as an ordinary compass.

It will be understood that I may accomplish the vertical and lateral adjustments of the marking elements in various ways, 100 the means disclosed in the accompanying drawing simply illustrating the preferred embodiment of my invention.

What I claim, and for which I desire to 105 secure Letters Patent, is:

1. In a drafting instrument, a supporting member, a plurality of marking elements mounted thereon, and common means for adjusting the different elements in opposite directions simultaneously one toward and 110 the other from said member.

2. In a drafting instrument, a plurality of marking elements parallel to each other, means for laterally spacing said elements relative to each other; and means for vertically adjusting the different elements in opposite directions simultaneously. 115

3. In a drafting instrument, the combination of a holder with a plurality of marking elements, means common to each of said elements for vertically adjusting them simultaneously, and means for locking said adjusting means whereby said elements will be held in their adjusted positions. 120

4. In a drafting instrument, the combination with a supporting member and a pair of marking elements arranged thereon to assume marking positions spaced apart, of common means connected to each of said elements for adjusting the same toward and 125 130

from said support so that one will be in its marking position and the other out of its marking position or both in their respective marking positions.

5. 5. In a device of the class described, the combination with a pair of marking elements and a supporting member therefor, of lateral adjusting means connected to one of said elements, and common adjusting means connected to each of said elements for adjusting the same simultaneously toward and from said support so that one will be in its marking position and the other out of its marking position or both in their respective 15 marking positions.

6. In a device of the character described, the combination with a plurality of marking elements, rack teeth carried by each of said elements, of means adapted to mesh with said rack teeth, whereby said marking elements may be vertically adjusted in opposite directions simultaneously.

7. A drawing instrument comprising adjacently mounted reciprocable marking elements arranged to assume marking position spaced apart, and common means for recip-

rocating said elements to bring either one into and the other out of its marking position.

8. A drawing instrument comprising adjacently mounted reciprocable marking elements, and common means for reciprocating said elements in opposite directions simultaneously to bring either one into and the other out of marking position. 30

9. A compass comprising a center point, a movable member having mounted thereon a plurality of marking elements arranged to mark upon adjacent portions of a surface one at a greater distance from said center point than the other, and common means for adjusting said elements toward and from said member so that one will be in its marking position and the other out of its marking position or both in their respective 40 marking positions simultaneously.

In testimony whereof I affix my signature in presence of two witnesses.

JOSEPH FRANCIS COLLINS.
